UNITED STATES PATENT OFFICE.

ANDERS GUSTAF GUNNAR SALENIUS, OF STOCKHOLM, SWEDEN, ASSIGNOR TO SEPARATOR AKTIEBOLAGET FAMA, OF STOCKHOLM, SWEDEN.

GEARING.

1,030,208.

Specification of Letters Patent. Patented June 18, 1912.

Original application filed January 5, 1910, Serial No. 536,490. Divided and this application filed July 5, 1911. Serial No. 636,967.

To all whom it may concern:

Be it known that I, ANDERS GUSTAF GUNNAR SALENIUS, Svedenborgsgatan 2, Stockholm, Sweden, have invented certain new and useful Improvements in Gearing, of which the following is a specification.

This invention relates to improvements in gearing.

The invention will be more particularly described in connection with the accompanying drawing and will be fully pointed out and ascertained in and by the appended claims.

This application is divided out from my application filed January 5, 1910, Serial Number, 536,490.

In the drawing:—Figure 1 is a sectional view of a portion of a centrifugal apparatus. Fig. 2 is a sectional view of a modified form of my invention with parts broken away.

Like numerals of reference designate similar parts throughout the drawing.

As shown, 1 designates the drum, 2 the core or the spindle, 3 the spiral spring, and 4 the pinion.

The thread of the spindle is formed by a resilient strip of material 3 spirally wound about the spindle 2 in a manner to mesh with the teeth of a pinion 4 and be driven thereby.

Referring to Fig. 1, the spiral spring is turnable on the spindle and is locked to it in that direction, in which the same is driven by the pinion engaging the same, but is released from the core or spindle, when the pinion is stopped. The spiral spring is not connected to the core or the spindle at any point, but is kept locked to the same in that direction, in which the same is driven by the pinion 4. The lower end of the spring forms a ratchet tooth 5 engaging in a ratchet notch 6 in a collar 7 on the core. If the pinion is stopped, the drum will continue in its rotation on account of its momentum, the coacting ratchet members permitting disengagement of the spring with the spindle.

It is evident, that the engagement of the driving spindle with the pinion by this arrangement will be yielding and without shocks.

In the form shown in Fig. 2 the thread 3 is secured at its lower end to the spindle by a screw 8.

I claim:

1. In combination with a spindle to be driven, a spiral spring loosely disposed on said spindle to form a worm, and a driving worm wheel having teeth meshing with winds of said spring to drive the spindle, said spring and spindle having coacting ratchet members arranged for engagement to lock the spring to the spindle when the latter is being driven, substantially as described.

2. In combination with a spindle to be driven, a spiral spring rotatable and longitudinally movable on said spindle and forming a worm thereon, and a driving worm wheel having teeth meshing with the winds of said spring to drive said spindle, said spring and spindle having coacting ratchet members arranged for engagement to lock the spring to the spindle when the latter is driven and permit release of the spindle for free rotation, substantially as described.

3. In combination with a spindle to be driven, a spring loosely disposed on said spindle and forming a worm, and a driving worm wheel having connection with the winds of said spring and shifting the same longitudinally of the spindle in one direction when driving the latter, said spring and spindle having coacting devices arranged to lock the spring on the spindle upon driving thrust being imparted by the wheel, substantially as described.

4. In combination with a substantially vertically disposed spindle to be driven, a spiral spring loosely disposed on said spindle and forming a worm and adapted to be shifted downwardly on said spindle, and a driven worm wheel having teeth meshing with the winds of said spring and shifting the spring longitudinally downwardly on the spindle when driving the latter, said spring and spindle having coacting devices, at the lower end of the spring, arranged to lock the spring on the spindle upon driving thrust being imparted by said wheel, substantially as described.

In testimony whereof I affix my signature in presence of two witnesses.

ANDERS GUSTAF GUNNAR SALENIUS.
